GAME APPARATUS

Hyman B. Lasting, Portsmouth, Va.
Application April 23, 1957, Serial No. 45,861

Term of patent 14 years

(Cl. D34—5)

Figure 1 is a perspective view of a game apparatus, showing my new design, the opposite side and rear having substantially the same appearance.

I claim:

The ornamental design for a game apparatus, as shown and described.
